ELECTROMAGNETIC FIELD GENERATOR

Filed April 12, 1930

INVENTOR
Franklin M. Henry
BY *Victor J. Evans*
ATTORNEY

UNITED STATES PATENT OFFICE

FRANKLIN M. HENRY, OF SAN FRANCISCO, CALIFORNIA

ELECTROMAGNETIC FIELD GENERATOR

Application filed April 12, 1930. Serial No. 443,793.

My invention relates to apparatus for producing electromagnetic fields and particularly alternating electromagnetic fields adapted for therapeutic use, and which at the same time may have many uses other than said therapeutic uses.

One object of my improvement is the provision of a simple and efficient device of the character mentioned.

10 Another object is the provision of a core and coil construction which will give a maximum strength of field at a particular point with a minimum temperature change in operation.

15 Another object is the provision of a device of this character having a maximum strength of field with a minimum weight and size.

Another object is the provision of means whereby major portions of the magnetic flux 20 from the core may be concentrated in desired portions of the pole piece.

25 A further object is the provision of means for compensating for contractions and expansions of parts of a device of the character mentioned.

A still further object is the provision of a novel means for connecting an electrical power supply to a coil of the character referred to.

30 Other objects and advantages will be apparent during the course of the following description.

In the accompanying drawings forming a part of this specification and in which like numerals are employed to designate like parts throughout the same,

35 Figure 1 is a diagrammatic view of the core and electrical circuit arrangement embodying one form of my invention.

40 Figure 2 is a vertical cross section of one form of my device, and diagrammatically illustrating the wiring arrangement.

Figure 3 is a top plan view of Figure 2.

45 Figure 4 is a fragmentary sectional view of the spool end.

Figure 5 is a horizontal cross section on line 5—5 of Figure 2.

50 Figure 6 is a horizontal cross section taken on line 6—6 of Figure 2, and

Figure 7 is a fragmentary side elevation of the lower end portion of my device.

In the accompanying drawings wherein for the purpose of illustration is shown a preferred embodiment of my invention, there is shown a layer wound coil 5 properly insulated from and disposed on a suitable core with an exposed pole piece at one end, said pole piece serving to facilitate directing an electromagnetic field to a desired position for use.

I preferably provide a laminated core made up of elongated sheets 10 as illustrated, or in any conventional manner. Each lamination 10 is provided with a portion 11 disposed at an angle to the part 10 and adjacent a pole piece 12. An important feature of my improvement is the disposition of the core lamination parts 11 with respect to the pole piece 12. The parts 11 may be bent sharply and arranged substantially parallel to the adjacent surface of pole piece 12, or bent at a greater angle to the parts 10 and engage the pole piece 12 nearer the lateral edges of the latter. The core laminations are 70 illustrated with the portions 11 of the laminations divided into two groups and directed in opposite directions, but these parts 11 may be divided into as many groups as may be desired and disposed in as many directions. 75

The parts 11 serve as means for directing major portions of the flux from the core to desired portions of the pole piece. When the parts 11 are bent sharply with little space 80 13 at the center of the core, as in Figure 2, the flux will be directed more strongly toward the central portion of the pole piece 12 and when the parts 11 are disposed less acutely the parts 11 facilitate directing most of the flux to edge portions of the pole piece 12, 85 see Figure 1.

The portions 11 of the core may be secured to the pole piece 12 in any desired manner. I have illustrated in Figure 7 convenient means by providing two screws 14 which extend through an adjacent spool end 15 and threaded into pole piece 12 so that the parts 11 are held firmly against pole piece 12.

The spool upon which the wire coil is mounted may be formed in any desirable man- 100

ner, but I prefer to make this spool up of two end pieces 15 and 16 with a tubular member 17 joining the two spool ends. The ends 15 and 16 may be countersunk as clearly illustrated in Figure 4, with an adjacent end of the tube 17 spun thereinto or otherwise secured thereto.

The spool made up of parts 15, 16, and 17 is of an insulating material, such as vulcanized fibre, or the like. On this spool is wound a plurality of layers of insulated wire. This winding may be arranged in the conventional or any desired manner to provide means for producing the electromagnetic flux in the core when an electric current is conducted through the wire of the coil. This coil is designated by the numeral 19 and it is diagrammatically shown in the drawing. At the end of the spool 15 which is adjacent pole piece 12, I preferably provide a thin insulation disc 20 to insure electrical insulation between the end of the coil 19 and the heads of screws 14.

The spool end 16 is threaded to receive two screws 21, which pass through a block 22 with the heads of screws 21 countersunk into block 22 as clearly illustrated in Figures 2 and 5. This provides a means for securing block 22 to spool end 16. A block 23 of disc form rests against block 22 and is held securely thereto by two screws 24. The screws 24 also pass through portions of the connector members 25. The connector members 25 are preferably set in a recess 26 so that the bend in portions thereof and the heads of screws 24 are below the outer surface of number 23. Perforations 27 are provided through the spool end 16 and disc 23 to conduct the ends of the wire in coil 19 out to the connector members 25 and are held securely to the latter by means of screws 28. The members 25 are adapted to connect with connector plugs, procurable in the open market and not illustrated.

The block 22 is of disc form except for cut away portions at opposite sides, providing recesses 22' in which end portions 19' of the wire of coil 19 are disposed in loops, so that if a wire end becomes broken at a screw 28 some of portion 19' may be pulled out and secured under the screw 28 again.

I provide a resilient covering 29 around the coil 19 and inside of a tubular casing 31 which surrounds all the parts except pole piece 12. This covering prevents the parts from becoming noisy due to expansions and contractions in use. The covering is preferably a single layer of a suitable cord of proper cross section to fill the space between the coil 19 and casing 31 in the manner described. The tubular covering 31 surrounds the coil covering 29 and has one of its ends abutting pole piece 12. The opposite end of covering 31 is secured to disc 23 as by screws 32.

65 This completes the unit which may be em-

ployed wherever it is desired for the purpose of giving therapeutic treatment.

It is to be understood that the form of my invention herewith shown and described is to be taken as a preferred example of the same and that various changes relative to the material, size, shape, and arrangement of parts may be resorted to without departing from the spirit of the invention or the scope of the subjoined claim.

Having thus far described my invention, I claim:

In a device of the character mentioned, a spool having cylindrical ends, a block secured to said spool end and narrower in one direction than said spool, a block of substantially the diameter of said spool end secured to the first mentioned block, there being openings in said spool end and block, and a coil of wire on said spool with end portions disposed in said openings with portions of the wire adjacent edges of the first mentioned block disposed in loops.

90 In testimony whereof I affix my signature.
